UNITED STATES PATENT OFFICE.

WALTER N. VANCE, OF CHICAGO HEIGHTS, ILLINOIS, ASSIGNOR TO DURAND STEEL LOCKER COMPANY, OF CHICAGO, ILLINOIS, A CORPORATION OF ILLINOIS.

LOCKER.

Application filed May 23, 1921. Serial No. 471,762.

To all whom it may concern:

Be it known that I, WALTER N. VANCE, a citizen of the United States, residing in Chicago Heights, in the county of Cook and 5 State of Illinois, have invented a new and useful Improvement in Lockers, of which the following is a specification.

This invention relates in general to lockers and similar construction, and has more 10 particular reference to the locking arrangement.

The invention has for its object broadly the provision of a keeper for receiving a padlock for locking the door closed, and 15 which will be of simple construction readily assembled into permanent relation with the door through the minimum number of assembling operations.

Another object of the invention is the provision of a keeper and handle lock of sturdy, durable construction which will require 20 minimum perforation of the door.

Another important object of the invention is the provision of a construction of the 25 character mentioned of pleasing appearance.

Numerous other objects and advantages of the invention will be apparent as it is better understood from the following description, which, taken in connection with the accompanying drawings, discloses a preferred embodiment thereof.

Referring to the drawings,

Figure 1 is a perspective view of a locker in which my present invention is embodied;

Fig. 2 is a section longitudinally thereof;

Fig. 3 is an enlarged section taken substantially on the line 3—3 of Fig. 1;

Fig. 4 is a section taken substantially on the line 4—4 of Fig. 3;

Figs. 5 and 6 are detail perspective views; and

Fig. 7 is a section taken just in advance of the keeper with the handle removed.

For the purpose of illustrating my invention I have shown on the drawing a locker 11 of any usual or preferred construction, having a manipulative handle 12 adapted to be locked against opening by an ordinary padlock 13. The handle 12 is provided in 45 the present instance with two lugs 14 and 15 adapted to extend through slots 16 and 17 in the locker door and into engagement with a latch bar 18 having a number of offset wedge teeth 19 adapted to engage in latch notches 21 of latch members 22 fastened to

the door frame and adapted to embrace the flange 23 of the door. The lower end 24 of the handle is flattened and it is this flattened end that carries the lock 15. This flattened end is adapted to move into and out of a keeper 25 shown in perspective in Fig. 6. This keeper is preferably formed of a single sheet of metal bent to provide two triangular side wings 26 connected by a back wall 27. At the bottom the ends or sides of the sheet are bent out to form flanges 28 which terminate short of the back wall forming a shoulder 29.

The keeper thus described may be inserted through the slot 17 and moved back until the shoulder 29 engages the edge 31 of the door material at the bottom of the slot. In this position the flanges 28 rest against the inner face of the door. The keeper is locked in position by driving a wedge or drift 75 along the face of the door and between the inner ends of the free edges 32 of the keeper. This shears the material as indicated at 33 and swages out locks 34 over the outer face of the door permanently and tightly locking the keeper in place. The keeper is provided with openings 35 for receiving the padlock and a similar opening 36 is provided in the flattened tail 24 of the handle. The keeper is of general triangular form and the back wall 27 may form a stop for the handle if desired.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a locker, the combination of a door having an aperture therein, a keeper disposed through the aperture from the rear, said keeper having a part engaging the inside of the door and a part swaged into interlocked relation from the front. 100
2. In a locker, the combination of an aper-tured door, a keeper having three integral sides and open at a fourth interlocked with said door and a movable member cooperat-ing therewith. 105
3. In a locker, the combination of a door, 110

a handle movable vertically of the door, and a triangular keeper extending through said door and adapted to receive said handle.

4. In a locker, the combination of a door, 5 a handle movable vertically of the door, and a triangular sheet metal keeper extending through said door and adapted to receive said handle.

5. In a locker, the combination of a door 10 having an aperture, a triangular keeper thrust through said aperture, the ends of said keeper being flanged to engage the inner face of the door, the material of the keeper adjacent the door being swaged to 15 engage the outer face of the door and a member adapted to move into said keeper.

6. In a locker, the combination of a door having an aperture, a keeper having a shoulder at one end and adapted to be disposed 20 through the door to engage the shoulder and the outer face of the door, the inner ends of said keeper being flanged to engage the inner face of the door and the forward edge of the keeper being swaged to engage the 25 outer face of the door.

7. In a locker, the combination of a door provided with a slot, a keeper composed of a sheet of metal bent to triangular form, the edges at one side being bent out to provide 30 door engaging flanges, the material of the keeper at the other free side being swaged outwardly over said flanges to lock the door thereagainst and a member adapted to move into said keeper.

8. In a locker, the combination of a door 35 provided with a slot, a keeper composed of a sheet of metal bent to triangular form, the edges at one side being bent out to provide door engaging flanges, the material of

the keeper at the other free side being 40 sheared and bent outwardly over said flanges to lock the door thereagainst and a member adapted to move into said keeper.

9. In a locker, the combination of a door, a 45 sliding handle therefor, a triangular keeper into and out of which said handle is adapted to slide, said handle and keeper being perforated to receive a lock.

10. In a locker, the combination of a door, a 50 sliding handle therefor, a triangular keeper into and out of which said handle is adapted to slide, said keeper being provided with a back wall forming a stop for said handle movement.

11. A keeper adapted to be attached to 55 a door and composed of two wings extending outwardly from said door, said wings being of general triangular form connected along the forward side.

12. A keeper adapted to be attached to a 60 door and composed of a sheet providing two side wings of general triangular form connected by a back wall along a triangular side of each side wall.

13. A door having a slot therein, a keeper 65 having parts extending through the slot and locked against the door, and a handle movable into and out of said keeper and having a part extending through and slideable in said slot.

14. A door having a slot therein, a triangular keeper having parts extending through the slot and locked against the door, and a handle movable into and out of said keeper and having a part extending through 70 and slideable in said slot.

WALTER N. VANCE.
